WATER SKI

Richard M. Cox, Knoxville, Tenn.

Application July 15, 1958, Serial No. 748,696

4 Claims. (Cl. 9—310)

2

the water ski will have a high degree of stability. The tubes further have upper curved or rounded surfaces 23.

Secured to the upper surface of the tubes in any suitable manner as for example by welding, is a plate 24, and the numerals 25 and 26 indicate heel and toe engaging members which are connected to the plate 24.

Arranged at the rear of the body member 11 and secured to the undersurface thereof as by welding is a triangular shaped fin which is indicated generally by the numeral 27. It is to be noted as shown in Figure 2 for example, that the rear portion of the fin 27 is of increased elevation, while the front portion of the fin 27 merges into the body member.

The numeral 28 indicates in Figure 5 a plug which can be used for closing off the rear end of each of the tubes so that the tubes will be air and watertight whereby the water ski 10 will be buoyant. Thus, in the event a person accidentally falls into the water, the ski 10 can be used as a life preserver so that the person will be kept afloat.

In addition, the water ski 10 is constructed of a plurality of hollow tubes such as aluminum tubes whereby the water ski is light in weight and rugged and efficient to use.

From the foregoing, it is apparent that there has been provided a water ski which is adapted to be made from suitable tubing such as the aluminum tubes shown in the drawings. However, the tubes can be made of other material besides aluminum.

It is noted that according to the present invention a plurality of tubes are secured together as by welding, and the tubes are shaped to include the major straight portion 12 and the front inclined or upwardly curved portion 13. The tubes are buoyant or hollow whereby

in the event a person accidentally falls into the water, the water ski 10 can be used as a life preserver or as a safety device since it will maintain the person in the water afloat until the person can reach shore or until a rescue can be effected.

According to the present invention the tubes 14 and 15 are of cylindrical formation as shown in Figure 4 for example, whereby the lower surfaces are rounded as at 22 and this rounded arrangement insures that the water ski will have increased stability so that there will be less likelihood of the water ski tipping over or moving from its proper position. The rear ends of the tubes can be closed off by means of the plugs 28 which can be secured in place in any suitable manner, as for example by welding, Figure 5. There is further provided the fin 27

which helps increase stability as well as provide a device that insures that the water ski will move through the water with the proper action.

The plate 24 which supports the heel and toe engaging members 25 and 26 is adapted to be secured as by

welding to the upper surfaces of the tubes, Figure 1. It is to be understood that a pair of the water skis of the present invention are adapted to be used by the water skier so that one water ski will be provided for each foot or leg.

The outer tube 15 is shaped to include the side section 16 and the upwardly curved front portion 17 as well as the interconnecting arcuate web 18. The inner tubes 14 include the straight portions 19 and the upwardly inclined or curved portions 20 which are secured as by

welding to the portions 17 and 18 of the outer tube 15. This arrangement provides a water ski of unitary construction wherein the ends of all the various tubes are closed off or made air and watertight so that the device will have the required or desired amount of buoyancy.

Furthermore, it is to be noted that the completed ski has no sharp edges or rough surfaces so that there will

This invention relates to a water ski.

The object of the invention is to provide a water ski which is adapted to be made of a plurality of tubes that are connected together such as aluminum tubes, whereby the ski will be buoyant so that the ski can be used as a life preserver in the event of an emergency.

Another object of the invention is to provide a water ski which includes a main body member that is made up of a plurality of hollow tubes that are secured together, and wherein the tubes are of cylindrical formation and have a rounded or curved lower surface so that the ski will have good stability and wherein the ski can be used with a greater degree of safety since in the event that a person falls in the water, the ski will support a person so that there will be less likelihood of drowning or other serious mishaps occurring.

A still further object of the invention is to provide a water ski which is constructed so that it can be used with greater safety than water skis of other types or constructions.

A further object of the invention is to provide a water ski that is extremely simple and inexpensive to manufacture.

Other objects and advantages will be apparent during the course of the following description.

In the accompanying drawings, forming a part of this application, and in which like numerals are used to designate like parts throughout the same.

Figure 1 is a perspective view of the water ski constructed according to the present invention.

Figure 2 is a side elevational view of the water ski of the present invention.

Figure 3 is a plan view of the water ski of the present invention.

Figure 4 is a sectional view taken on the line 4—4 of Figure 1.

Figure 5 is a sectional view taken on the line 5—5 of Figure 3.

Referring in detail to the drawings, the numeral 10 designates the water ski of the present invention, and the water ski 10 includes a body member which is indicated generally by the numeral 11, and the body member 11 includes a major straight portion 12, and a front curved portion 13.

The water ski consists of a plurality of inner tubes 14, and an outer tube 15. The outer tube 15 includes a pair of spaced parallel side sections 16 which have front curved portions 17 that extend upwardly, and the curved portions 17 are interconnected by means of an arcuate or curved web or connecting portion 18.

As shown in the drawings, the inner tubes 14 include straight sections 19 and upwardly curved front sections 20 which are secured as by welding to the web 18.

The various tubes such as the tubes 14 and 15 are arranged in the same plane as for example as shown in Figure 4, and these tubes are secured together as by welding. The tubes are of hollow cylindrical formation and have lower rounded surfaces 22 which insure that

be no danger of a person accidentally hurting himself or herself on such sharp or rough edges and the various rounded surfaces help insure that there will be less likelihood of a person hurting himself or herself when using the water ski.

The parts can be made of any suitable material and in different shapes or sizes.

An important feature of the present invention is the safety factor. Thus, with a minimum displacement of 191 cu. in. of air per ski, the ski will serve as a life preserver in case of emergency. The ski is adapted to be constructed primarily of aluminum tubing, but it can also be constructed of any suitable material such as Fiberglas or the like. The convex surfaces or curved surfaces of the tubing increase the lateral stability of the user. The fin 27 has a triangular shape so that it tapers or merges into the ski as for example as shown in Figure 2. The fin 27 can also be made of aluminum and can be welded onto the ski approximately 6 inches from the rear end.

When using skis such as the skis of the present invention persons can ski safely and with increased pleasure and satisfaction and the skis will support a heavy person or load. Furthermore, the skis may be anodized so as to help insure that the aluminum tubing will not be subject to corrosion from salt water or the like.

Minor changes in shape, size and rearrangement of details coming within the field of invention claimed may be resorted to in actual practice, if desired.

I claim:

1. A water ski comprising a body member including a plurality of hollow tubes, the major portions of said tubes being straight and lying in the same plane, said tubes including inner tubes, and an outer tube having spaced parallel side sections, the side sections of said outer tube being straight and being arranged in spaced parallel relation with respect to each other, the front portions of said side sections being curved upwardly and being interconnected by an arcuate web, the front portions of said inner tubes being curved upwardly and secured to said web, and a fin secured to the lower rear portion of said body member.

2. A water ski comprising a body member including a

plurality of hollow tubes, the major portions of said tubes being straight and lying in the same plane, said tubes including inner tubes, and an outer tube having spaced parallel side sections, the side sections of said outer tube

5 being straight and being arranged in spaced parallel relation with respect to each other, the front portions of said side sections being curved upwardly and being interconnected by an arcuate web, the front portions of said inner tubes being curved upwardly and secured to said web, and a fin secured to the lower rear portion of said body member, said fin having a triangular shape and wherein the rear portion of the fin is of increased size, the front of the fin merging into the body member.

15 3. The structure as defined in claim 2, and further including a plate secured to the upper surface of said tubes, and heel and toe engaging members connected to said plate.

20 4. A water ski comprising a body member including a plurality of hollow tubes, the major portions of said

tubes being straight and lying in the same plane, said tubes including inner tubes, and an outer tube having spaced parallel side sections, the side sections of said outer tube being straight and being arranged in spaced parallel relation with respect to each other, the front

25 portions of said side sections being curved upwardly and being interconnected by an arcuate web, the front portions of said inner tubes being curved upwardly and secured to side web, and a fin secured to the lower rear portion of said body member, said fin having a triangular

30 shape and wherein the rear portion of the fin is of increased size, the front of the fin merging into the body member, a plate secured to the upper surface of certain

35 of said tubes, heel and toe engaging members connected to said plate, said tubes being airtight, and plugs closing the rear ends of said tubes, said tubes being made of aluminum.
